TOY ROCKET CONTROL PANEL

Anthony J. Patane, Oneida County, N. Y.

Application November 18, 1954, Serial No. 33,151

Term of patent 7 years

(Cl. D34—15)

Fig 2

Figure 1 is a perspective view of a toy rocket control panel, showing my new design; and

Figure 2 is an end view thereof.

The back thereof is plain or conventional.

I claim:

The ornamental design for a toy rocket control panel, as shown and described.
